SPLIT-CORE VOLT-AMMETER

Harvey A. Schwartz, Merrick, and Franklyn Jacoby, New York, N.Y., and Ernest Calafano, Maywood, N.J., assignors to Soss Manufacturing Company, Detroit, Mich., a corporation of Nevada

Filed Aug. 29, 1966, Ser. No. 3,637

Term of patent 14 years

(Cl. D26—1)

T1Q. 1.

T1Q. 2.

T1Q. 3.

T1Q. 4.

T1Q. 5.

T1Q. 6.

FIG. 1 is a front view of a split-core volt-ammeter showing our new design.

FIG. 2 is a right side view thereof.

FIG. 3 is a plan view thereof.

FIG. 4 is a rear view thereof.

FIG. 5 is a left side view of FIG. 1.

FIG. 6 is a bottom view thereof.

FIG. 7 is a front view of a modified form of the split-core volt-ammeter shown in FIGS. 1 to 6 inclusive.

FIG. 8 is a right side view of FIG. 7.

FIG. 9 is a left side view of FIG. 7.

FIG. 10 is a top view of FIG. 7.

FIG. 11 is a bottom view thereof.

The rear view of the embodiment of FIGURES 7 to 11 is the same as FIG. 4.

We claim:

The ornamental design for a split-core volt-ammeter, as shown and described.
